PRESS OPERATING AND CONTROL
MECHANISMClifton S. Malott, Jr., Norwood, Ohio, assignor to
The American Laundry Machinery Company,
Norwood, Ohio, a corporation of Ohio

Application October 30, 1935, Serial No. 47,447

17 Claims. (Cl. 68—9)

This invention relates to a pressing machine of the type used in pressing garments and laundered articles.

My invention provides a novel press structure and control mechanism in the type of pressing machine wherein a pair of coacting pressing members are movable laterally into and out of registration and movable into and out of pressure engagement when in registry. In such a machine I provide novel means for producing the lateral movement between the pressing members and also novel means for causing pressure engagement between them. My invention is particularly applicable to a type of pressing machine which provides two relatively stationary pressing members spaced apart laterally so as to coact alternatively with one or the other of two spaced coacting pressing members carried by a support for lateral movement into and out of registry with the first named pressing members. In such a machine I arrange the coacting members so that while one pair is in registration the other pair is out of registration with a pressing member exposed for the removal of a processed article and the application of an article to be processed. In this type of machine the present invention provides novel means for movement of one pair of pressing members into and out of registration with other coacting pressing members by means of a movable support and novel means on the support for causing pressing engagement of registering pressing members.

My invention also provides novel control mechanism for the type of pressing mechanism outlined above and the novel features thereof will be pointed out in the accompanying specification and the essential features will be set forth in the claims.

In the drawing, Fig. 1 is a view in front elevation partly in section of a machine embodying my invention; Fig. 2 is an enlarged sectional view of a portion of the mechanism of Fig. 1; Fig. 3 is a view taken along the line 3—3 of Fig. 2; while Fig. 4 is a view taken along the line 4—4 of Fig. 1.

Certain features of my invention are applicable to a single pair of pressing members relatively movable laterally into and out of registration with each other and when in registration movable into and out of pressure engagement. However, I have chosen to illustrate my invention as applied to a machine comprising a frame 10 upon which are supported in a stationary manner a pair of pressing heads 11 and 12 which may be suitably heated if desired. Mounted upon the frame 10 are a pair of spaced pressing beds 13

and 14 which are adapted to be carried by a support or carriage 15 for lateral movement along the frame. The head supports are at the rear of the frame having a clear path beneath the heads. It will be noted that the heads are spaced apart a sufficient distance so that when one pair of pressing members, for instance 12 and 14 as shown in Fig. 1, is in registration, the bed 13 is in exposed position between the pressing heads so that the operator may arrange material thereupon.

Means is provided for causing lateral movement of the pressing beds into and out of registry with their respective heads. In the form shown a cylinder and piston motor is built into 15 and forms part of the support or carriage 15, although it will be readily understood that other arrangements of the motor and carriage may be provided which will provide the same results. I so arrange this cylinder and piston motor that one of the elements thereof is carried by the frame while the other element is carried by the bed support. In the present instance the cylinder 15a is on the support and the piston 15b is rigidly connected with the frame. In the form shown the piston connection comprises conduits 16 and 17 which at their innermost ends are threaded into the piston and at their outermost ends are supported by brackets 10a and 10b on the frame. The piston 15b has cored 30 passages 18 and 19 in its opposite end faces so that fluid entering by conduit 16 and passage-way 18 exerts a pressure in the right hand end of cylinder 15a to cause motion of support 15 to the right, while fluid entering conduit 17 through 35 passageway 19 exerts pressure at the left end of cylinder 15a to cause motion of support 15 to the left. The conduits 16 and 17 where they pass through the heads of cylinder 15a are provided with substantially fluid-tight packing glands 20 and 21. The carriage or support 15 is provided with wheels 22 which travel on rails 23 carried by the frame. The above described mechanism for providing lateral movement of the pressing beds might be utilized to carry a bed into registration with one of the pressing heads which might thereafter be moved downwardly to cause pressure engagement. However, in the form shown the pressing heads are stationary and the means for causing final pressure is mounted upon 50 the movable support or carriage 15.

For causing vertical movement of the pressing beds, motor means for each bed is mounted on the carriage 15. The motor means comprises cylinder and piston motors, one for each bed, and

as these are alike one will be described and the other will be marked with similar characters. Bed 13 is raised and lowered by motor 24 which comprises a cylinder 24a rigid with the support 5 15 and housing a piston 24b whose piston rod 24c engages the pressing bed. The lower head of cylinder 24a is provided with an outlet port 24d and an inlet port 24e. Directly beneath the cylinder 24a is formed a valve chamber for the 10 reciprocating valve 25 which is biased by a suitable spring so as to normally exhaust cylinder 24a through the port 24d and an outlet port 25a which leads from the left end of the valve chamber. The valve 25 is actuated by a stem 25b 15 as will be presently described. A port 26 in the wall of cylinder 15a lies directly opposite the inlet port 24e and the valve 25 normally closes this port 26 under the bias of its actuating spring. The port 26 is also closed by piston 15b when 20 the pressing bed 13 is in exposed position but upon relative movement in registration-producing direction between piston 15b and cylinder 15a it will be seen that the port 26 will be opened.

The mechanism connected with pressing bed 25 14 is similar to that already described, the motor and associated parts being designated by the numeral 27 with suitable suffixes, the valve mechanism being shown at 28 and the port at 29. It will be noted that the parts for moving beds 13 and 14 30 are turned in the right and left hand directions to bring them in their proper positions.

Means is provided for controlling the flow of pressure fluid through conduits 16 and 17 so as to provide a flow through one while simultaneously exhausting the other. The mechanism shown comprises valve casings 30 and 31 mounted on a suitable bracket connected with the frame, each valve casing having similar parts which are similarly designated while one only is described. Casing 30 has an inlet port 30a, an outlet port 30b, and a piston valve 30c which is movable to two positions, one for establishing flow and the other for establishing exhaust. A yoke 32 is pivotally mounted on the bracket and connected at its opposite ends with piston valves 30c and 31c, and movement of the yoke by its handle 32a will move one of the piston valves into fluid supply position while simultaneously moving the other piston valve into fluid exhaust position.

Means is provided for latching a pressing bed in position registering beneath its associated head automatically upon the pressing members reaching registry and this latching mechanism is automatically disengaged upon completion of a pressing operation. The mechanism shown comprises a latch member 24f connected with the movable support 15 and in the present instance being rigid with the cylinder 24a. A coacting latch member 60 33 is pivotally mounted on the bracket 10a. A spring 33a biases the latch toward its engaging position and the latch has a laterally extending arm 33b which is engageable by a stem 13a on the bed 13 as the bed moves downwardly out of 65 pressing engagement. The arrangement of the mutually engaging surfaces on the latch members 24f and 33 is such that as these members pass one over the other upon bed 13 registering beneath head 11, latch 33 is moved in a clockwise direction 70 sufficiently to lower the arm position 33b to a point where stem 13a will pass idly over it. Then upon complete engagement of the latch and movement of the bed 13 toward head 11 the latch remains engaged until upon opening of the pressing members and downward movement of bed 13, the stem 75

13a strikes the latch portion 33b, rotating the latch 33 in a clockwise direction and again disengaging the latch. Similar parts are shown at the other end of the machine and designated 27f, 34, 34a, and 34b respectively. 5

With the parts in the position of Fig. 1 and with motive fluid under pressure being supplied at 30a and 31a, the operation of the mechanism is as follows:

The operator arranges the lay of the work upon 10 bed 13 and moves yoke 32 in a counter-clockwise direction. This supplies motive fluid to the right hand face of piston 15b through conduit 31a, valve casing 31, conduit 16 and passageway 18. At the same time the left face of piston 15b and the portion of the cylinder contiguous thereto is placed in communication with exhaust through passageway 19, conduit 17, valve casing 30 and port 30b. There is then a tendency for cylinder 15a and the carriage or support 15 to move toward the right 20 under the influence of the fluid supplied through conduit 16. However, this is ineffective as long as latch members 34 and 27f are engaged. It will be noted that in the position of the parts in Fig. 1, ports 27e and 29 are open and establish 25 communication between cylinder 15a and cylinder 27a. Cylinder 27a therefore exhausts and bed 14 follows piston 27b downwardly until stem 14a engages latch portion 34b and disengages latch 34 from the coacting portion 27f. The fluid 30 pressure in the right hand end of cylinder 15a is then effective to move the support 15 toward the right carrying bed 13 into registry with head 11. During this movement port 26 is opened and upon reaching registration valve stem 25b strikes 35 a portion of bracket 10a moving valve 25 to open port 24e and to close port 24d. This places these parts in the relative position already seen in Fig. 1 in connection with the movement of members 12 and 14 into pressure engagement. That is to 40 say, fluid will then flow from the right hand end of cylinder 15a through ports 26 and 24e into cylinder 24a causing a lifting of piston 24b and bed 13 until engagement occurs between the bed and the head 11. The parts will remain in this position until valves 30c and 31c are again reversed 45 which will return the parts to the position of Fig. 1 in a manner analogous to that already described.

The operator is thus enabled to stand at the 50 center of the machine and arrange the work upon the beds as they are alternately exposed before her and by manipulation of the yoke 32 causes a movement of the beds to the right or left as described and each movement of the bed 55 into registration with its coacting head is followed automatically by movement into pressure engagement which is maintained until the operator again moves the yoke 32.

What I claim is:

1. In a pressing machine, a frame, a support movable on said frame in a path, two spaced pressing members on said support and movable relative thereto, two spaced pressing members on said frame and arranged along said path to 65 alternatively coact with one of said first named pressing members while exposing the other, means for moving said support alternatively to place one or the other of the coacting pairs of pressing members in registry, and motor means 70 carried by said support for moving one of said first named pressing members relative to said support and into engagement with the registering pressing member.

2. In a pressing machine, a frame, a support 75

movable on said frame in a path, two spaced pressing members on said support and movable relative thereto, two spaced pressing members on said frame and arranged along said path to alternatively coat with one of said first named pressing members while exposing the other, means for moving said support alternatively to place one or the other of the coacting pairs of pressing members in registry, motor means carried by said support for moving one of said first named pressing members relative to said support and into engagement with the registering pressing member, a control member for said motor means, and means for automatically actuating said control member upon registration of coacting pressing members.

3. In a pressing machine, a frame, a support movable on said frame in a path, two spaced pressing members on said support and movable relative thereto, two spaced pressing members on said frame and arranged along said path to alternatively coat with one of said first named pressing members while exposing the other, means for moving said support alternatively to place one or the other of the coacting pairs of pressing members in registry, two fluid motors carried by said support, each of said motors being arranged to move one of said first named pressing members relative to said support and into engagement with the registering pressing member, a control member for each motor, and means for automatically actuating a control member upon registration of its associated pressing member with a coacting pressing member.

4. In a pressing machine, a frame, a pressing member thereon, a support movable on said frame, a pressing member on said support and movable thereby into and out of registry with said first named pressing member, means for moving said support to register said pressing members, a motor carried by said support and operatively connected with said second named pressing member to move the same relative to said support into engagement with said first named member when in registry therewith, and operating means for said motor.

5. In a pressing machine, a frame, a pressing member thereon, a support movable on said frame, a pressing member on said support and movable thereby into and out of registry with said first named pressing member, means for moving said support to register said pressing members, a cylinder and piston motor carried by said support and operatively connected with said second named pressing member to move the same relative to said support into engagement with said first named member when said members are in registry, means for supplying pressure fluid to said motor, a control member for said fluid supply, and means for automatically actuating said control member upon registration of said pressing members.

6. In a pressing machine, a frame, a support movable on said frame in a path, two spaced pressing members on said support, two spaced pressing members on said frame and arranged along said path to alternatively coat with one of said first named pressing members while exposing the other, a motor for moving said support alternatively to place one or the other of the coacting pairs of pressing members in registry, said motor having cylinder and piston elements, one of said elements being connected with said support, the other of said elements being connected with said frame, fluid supply

means for said motor, and means for causing pressing engagement between registering pressing members.

7. A pressing machine as in claim 6, and including a fluid supply line for said motor rigidly connected with that one of said elements which is connected with the frame.

8. In a pressing machine, a frame, a support movable on said frame in a path, two spaced pressing members on said support, two spaced pressing members on said frame and arranged along said path to alternatively coat with one of said first named pressing members while exposing the other, a motor for moving said support alternatively to place one or the other of the coacting pairs of pressing members in registry, said motor having cylinder and piston elements, one of said elements being connected with said support, the other of said elements being connected with said frame, fluid supply means for said motor, and fluid actuated means for each pressing member on said support for moving the pressing surface thereof into engagement with a registering pressing member.

9. A pressing machine as in claim 8, and including means for establishing fluid supply conduit communication with one of said fluid actuated means by movement of said motor in a direction to register the pressing member actuated by said one means with a coacting pressing member.

10. In a pressing machine of the class described, a frame, a pressing member thereon, a support movable on said frame, a pressing member on said support and movable thereby into and out of registry with said first named pressing member, a motor for moving said support, said motor having cylinder and piston elements, one of said elements being connected with said support, the other of said elements being connected with said frame, fluid supply means for said motor, and means for causing pressing engagement between said pressing members when they are in registry.

11. In a pressing machine of the class described, a frame, a pressing member thereon, a support movable on said frame, a pressing member on said support and movable thereby into and out of registry with said first named pressing member, a motor for moving said support, said motor having cylinder and piston elements, one of said elements being connected with said support, the other of said elements being connected with said frame, fluid supply means for said motor, and fluid actuated means on said support for moving the pressing surface of the member thereon into engagement with the pressing member on the frame when said members register.

12. A pressing machine as in claim 11, and including means for establishing fluid supply conduit communication with said fluid actuated means by movement of said motor in registration-producing direction.

13. A pressing machine comprising a frame, a bed support arranged to travel in a path therewith, two spaced pressing beds upon said support, two spaced pressing heads arranged along said path alternatively to coat with one of said beds while exposing the other of said beds, said support comprising a cylinder, a piston in said cylinder rigidly connected to said frame by fluid conduits at its opposite ends, said conduits having sliding fluid-tight engagement with the ends

of said cylinder, said cylinder and piston being arranged to provide support travel sufficient to register each of said beds alternatively with one of said heads, means for causing pressing engagement between a registering bed and head, and means for supplying fluid to said conduits.

14. A pressing machine as in claim 13, and in which each pressing bed is movable vertically relative to said support, the means for causing pressing engagement between a registering bed and head includes a cylinder and piston motor on said support, there being an operative connection between said last named motor and a bed for raising the latter into engagement with a head, and means for supplying fluid to said last named motor when its associated bed registers with a head.

15. A pressing machine as in claim 13, and in which each pressing bed is movable vertically relative to said support, the means for causing pressing engagement between a registering bed and head includes a cylinder and piston motor on said support, there being an operative connection between said last named motor and a bed for raising the latter into engagement with a head, and means for supplying fluid to said last named motor when its associated bed registers with a head.

with a head, said last named means including a control member arranged for automatic actuation by movement of the said bed into registry.

16. A pressing machine as in claim 13, and in which each pressing bed is movable vertically relative to said support, the means for causing pressing engagement between a registering bed and head includes a cylinder and piston motor on said support, there being an operative connection between said last named motor and a bed for raising the latter into engagement with a head, and means for supplying fluid to said last named motor when its associated bed registers with a head, said last named means including a port controlled by relative movement between 15 said first named piston and cylinder.

17. In a pressing machine, a pair of coacting pressing members relatively movable laterally into and out of registration and relatively movable into and out of pressure engagement, means 20 for causing both of said movements, latch means engageable to hold said members in registration, and means for disengaging said latch means by relative movement of said members out of pressure engagement.

CLIFTON S. MALOTT, JR.
